UNITED STATES PATENT OFFICE.

ANTHONY PETOIO, OF NEWARK, NEW JERSEY.

WRENCH.

Application filed April 6, 1923. Serial No. 630,356.

To all whom it may concern:

Be it known that I, ANTHONY PETOIO, a citizen of the United States, residing at Newark, in the county of Essex and State of New Jersey, have invented certain new and useful Improvements in Wrenches, of which the following is a specification.

This invention relates to improvements in wrenches.

10 The primary object of this invention is the provision of a durable and accurate wrench embodying quick adjusting means which will not interfere with the efficiency of the wrench in effecting slight adjustments.

15 A further object of this invention is the provision of a quick adjusting wrench embodying a practical and durable association of parts which may be economically manufactured.

20 Other objects and advantages of this invention will be apparent during the course of the following detailed description.

In the accompanying drawing, forming a part of this specification, and wherein similar reference characters designate corresponding parts throughout the several views.

Figure 1 is a side elevation, partly in section, showing important details of the improved wrench.

30 Figure 2 is a bottom plan view of the improved wrench.

Figure 3 is a cross sectional view, taken substantially on the line 3—3 of Figure 1.

35 Figures 4 and 5 are perspective view of details of this invention, included as parts of a movable jaw structure embodied therein.

40 In the drawing, wherein for the purpose of illustration is shown but the preferred embodiment of this invention, the letter A generally designates the improved wrench, which may include an elongated shank 10, preferably polygonal in cross section and having the laterally extended rigid or fixed jaw 11 at one end thereof. The lower or bottom edge 12 of the shank 10, from which the rigid jaw 11 is offset is preferably provided with threads 13 inclined slightly with respect to the run of the shank 10.

45 A movable jaw structure 15 is preferably slidably mounted upon the shank 10, which includes the movable jaw element 16, and releasable adjusting mechanism 17.

50 The movable jaw 16 is preferably of metal construction, and has a polygonal shaped passageway 20 extending therethrough for

snugly and slidably receiving the wrench shank therein, whereby the jaw element 16 when mounted upon the shank 10 for sliding longitudinally thereof will be prevented from lateral shift or rocking upon said shank. A reduced article engaging portion 23 extends laterally from the threaded edge 12 of the shank 10, as a part of the jaw element 16, in facing relation toward the fixed 60 jaw 11 substantially as is illustrated in Figure 1 of the drawing. On the portion of the jaw element 16 which extends laterally outwardly from the shank opening 20 directly opposed recesses 25 are provided on opposite 65 sides of the element 16 which open at the rear edge 26 of the jaw element 16. The portion 27 of the jaw element 15, intermediate the opposed recesses 25 is preferably provided with a slot 29 which extends at right 70 angles to the run of the shank receiving passageway 20.

Referring to the quick adjusting means 17, the same preferably includes a body or casing 30 provided with a polygonal shaped 80 passageway 31 extending therethrough which snugly and slidably receives the thickness of the shank 10, but as the height of the passageway is greater than the width of the shank 10, the casing 13 may be moved transversely of the jaw shank 10, as is obvious from Figure 1 of the drawing. A spring member 35, preferably of good grade 85 clock spring is preferably carried by the top wall 36 of the body 30, within the passageway 31; said spring 35 being connected to said top wall 36 intermediate its ends, as by means of a rivet or other securing element 38, so that the ends 39 of said spring, when the adjusting means 17 is disposed upon the shank 10, will engage the outer edge 40 of the shank 10. A recess 45 is provided in the housing or casing 30, which intersects the passageway 31, and provides the outwardly or laterally extending legs 46 and 47. A 90 pintle member 50, in the form of a detachable screw or bolt, is provided for connection to the legs 45 and 47 of the casing 30, extending transversely of the recess 45 and upon which an adjusting thumb nut 54 is rotatably mounted within the recess 45. It is preferred that the leg 46 be provided with a screw threaded aperture 56 open to the recess 45 and in aligning relation with an opening 57 in the leg 47, so that the screw or 95 pintle member 50 may be inserted through the opening 57 for screw threaded engage-

ment at its inserting end in the screw threaded opening 56.

From the above description of the adjusting means 17, it is apparent that the flat spring 35 normally urges the threads of the thumb nut 54 into engagement with the threads 13 of the wrench shank 10, so that upon rotation or oscillation of the thumb nut 54, the casing 30 may be fed longitudinally of the shank 10. The laterally extending leg 46 of the casing 30 is provided with the forwardly extending lugs or arms 60, provided with aligning apertures 61 therein; said lugs 60 being provided for movable insertion in the opposed recesses 25 of the movable jaw element 16. Within the recesses 25, the lugs 60 are not hampered as to movement. A pin 62 is provided for connection of the adjusting mechanism 17 to the movable jaw mechanism 16, as by insertion through the aligning apertures 61 of the casing 30 and the slot 29 of the movable jaw element 16. When in this relation of assembled parts, the front face 70 of the casing 30 engages the rear edge 26 of the movable jaw 16, while the spring 35 also maintains the pivot pin 62 in its most upward position within the slot 29, proximate the screw threaded side 12 of the shank 10, and substantially as is illustrated in Figure 1 of the drawing.

When it is desired to quickly slide the movable jaw construction 15 for a considerable distance along the wrench shank 10, the operator needs merely to apply pressure upon the casing 30 in proximity to the rivet 38 thereof, which will depress the spring 35 and remove the threads of the thumb screw 54 from engagement with the threads of the wrench shank 10; this operation being permitted by the slideable pivot connection of the adjusting mechanism 17 with the jaw element 16 as hereinbefore described.

From the foregoing description of this invention, it is obvious that a practical type of quick adjusting wrench has been provided, which includes a mechanism attached to a movable jaw element so as not to weaken the jaw element in the slightest and operating therewith so that the same may be released to permit relatively long movements of the jaw upon the wrench shank, and yet being susceptible of engagement with the wrench shank, as to permit accurate and slight adjustments of the movable jaw element with relation to the fixed jaw element of the wrench.

Various changes in the shape, size and arrangement of parts may be made to the

form of invention herein shown and described, without departing from the spirit of the invention or the scope of the claims.

I claim:

1. A wrench comprising a threaded shank having a fixed jaw thereon, a movable jaw slidable longitudinally of said shank, a casing having forwardly extending lugs, means connecting said lugs to said movable jaw to permit relative movement of the movable jaw and casing transversely of the shank, an adjusting nut carried by said casing, and spring means carried by said casing engaging said shank normally urging said nut into engagement with the threads of said shank, said casing upon flexing of said spring adapted to move said nut out of engagement with the threads of said shank whereby the movable jaw may be shifted longitudinally of the shank:

2. As an article of manufacture, a wrench including a threaded shank having a fixed jaw on an end thereof, a movable jaw having a passageway for slidably receiving a shank therethrough whereby the jaw may be moved longitudinally but not laterally with respect to said shank, said movable jaw providing opposed recesses on opposite sides thereof with a slot extending through the portion of said movable jaw between said recesses, said slot extending transversely of the shank run, a casing including a passageway for slidably receiving the shank therethrough, said passageway being of such dimension as to permit movement of the casing transversely of the shank in the plane of the movable jaw, an adjusting screw rotatably carried by said casing adjacent the threads of said shank, spring means within the passageway of said casing normally engaging said shank to maintain the adjusting nut in engagement with the threads of said shank, forwardly extending fingers carried by said casing for movable disposition in the recesses at the opposite sides of said movable jaw, and a pin transversely carried by said forwardly extending fingers extending into the slot of said movable jaw, said casing when transversely moved on said shank against the action of said spring thereon adapted for slideable pivotal movement of the pin in the slot of said movable jaw, whereby the adjusting nut of said casing may be laterally moved out of threaded engagement with said shank to permit quick adjusting of the movable jaw on the wrench shank.

ANTHONY PETOIO.
